UNITED STATES PATENT OFFICE.

ERDIX ROUNDS, OF OWENSBORO, KENTUCKY, ASSIGNOR OF ONE-HALF TO GUNTHER-WRIGHT MACHINE COMPANY, OF OWENSBORO, KENTUCKY, A CORPORATION.

CYLINDER-HEAD FOR EXPLOSIVE-ENGINES.

1,129,605.

Specification of Letters Patent. Patented Feb. 23, 1915.

Application filed April 14, 1913. Serial No. 761,033.

To all whom it may concern:

Be it known that I, ERDIX ROUNDS, a citizen of the United States, residing at Owensboro, in the county of Daviess and State of Kentucky, have invented certain new and useful Improvements in Cylinder-Heads for Explosive-Engines, of which the following is a specification.

My invention relates to improvements in cylinder heads for explosive engines, for either a single or multiple cylinder engine, comprising a hollow casing, and inlet and exhaust conduits of unitary and integral construction.

An object of my invention is to provide a cylinder of an explosive engine with a fuel conduit, an exhaust conduit, the valve seats or pockets integrally formed within the head, with the conduits separated from each other, and the exterior walls of the head providing a surrounding conduit or jacket space for the circulation of a cooling medium.

Another object of my invention is to provide a cylinder head of an explosive engine, having unitarily formed therewith a fuel conduit, and an exhaust conduit, each surrounded and separated from the exterior walls of the head by a jacket space. The conduits each have a terminal at one end of the cylinder head adjacently disposed.

Another object of my invention is to provide a cylinder head of an explosive engine with a fuel conduit and an exhaust conduit unitarily and integrally formed within the cylinder head, and an exhaust chamber at the terminal of the exhaust conduit surrounded by an air conduit or jacket space, with an overflow pipe centrally disposed in the exhaust chamber, and in communication with the jacket space of the cylinder head. The end or mouth of the overflow pipe, at a point above the plane or liquid level within the jacket space of the head, for the escape of the circulated cooling medium, creates a vacuum chamber and outlet beyond the cylinder head area to prevent any accumulation of air pockets within the cylinder head. This insures a complete immersion of the heated parts of the cylinder head at any angle at which the engine may be stationed or disposed, which is primarily advantageous when the engine is used for marine purposes.

Another object of my invention is to pro-

vide a cylinder for a multiple cylinder engine of unitary manifold form, with a manifold fuel conduit and a manifold exhaust conduit integrally formed within the head, and each conduit surrounded by a jacket space separating the walls of the conduits from each other and from the walls of the cylinder head, so as to enable the conduits to be substantially immersed or surrounded by a cooling medium.

The structure as a whole offers compactness, the elimination of numerous connections from one head to a second, insulates the exhaust conduit, prevents direct contact with a heated conduit, to the injury or discomfiture of the operator, and also serves to muffle the noise of the escaping exhaust gases.

The features of my invention are more fully set forth in the description of the accompanying drawings, which illustrate the cylinder head of manifold form for a triple cylinder engine, but the invention herein is not dependent upon any particular number of cylinders.

Figure 1 is a central horizontal section of my improved manifold cylinder head. Fig. 2 is a section on line *x*, *x*, Fig. 1, illustrating a portion of the cylinder attached thereto. Fig. 3 is a section on line *v*, *v*, Fig. 1. Fig. 4 is a section on line *w*, *w*, Fig. 1. Fig. 5 is a central horizontal section of a modified form in which the valve ports are arranged in a longitudinal plane instead of transverse to the longitudinal plane of the head, as illustrated in Fig. 1. In this view, an exhaust head is shown attached to the exhaust conduit and a carbureter or vaporizer to the fuel conduit. Fig. 6 is a section on line *a*, *a*, Fig. 5. Fig. 7 is a central vertical section through the exhaust head. Fig. 8 is a section on line *b*, *b*, Fig. 7.

The cylinder head herein shown is designed to be applicable to a type of explosive engine, shown and described in an application, filed by me March 13, 1911, Serial No. 614,146, wherein certain disclosure herein was included in said application and is divisional therefrom. The form of head, as shown in Fig. 1, also contains provisions for a specific type of sparkler mechanism included in said application but which is now contained in a separate application filed on even date herewith. The head can be arranged for the various types of sparkler

mechanism well known to the art, and the particular embodiment herein is not considered characteristic to the general features of my invention.

5 1 represents the cylinder head, and as heretofore expressed, is designed for a triple cylinder engine, and, therefore, certain elements are represented in duplicate, and the description herein for one, equally applies to a second, unless specifically defined.

10 The cylinder head comprises a unitary structure of integrally formed conduits and preferably interior of the cylinder head, which may be termed as of hollow form, to 15 provide a surrounding jacket space around the conduits. The head is removably secured to the cylinder or cylinders and its water jacket communicates with the water jacket of the cylinders. This produces a 20 compact structure, with the portions, which becomes highly heated, water jacketed to be surrounded by a cooling medium, and provision is made to initially direct the incoming cool water toward and against such 25 parts or portions of the engine.

2 2 represents a fuel conduit or passage, having an inlet port 3, at one end of the cylinder head for adjacently securing a carbureter or vaporizer. The conduit is extended longitudinally within the cylinder head, and preferably at one side thereof, communicating at the lower portion thereof with the inlet ports 4, 4^a, and 4^b of the series, each leading into the top of a cylinder 35 5 of an engine. This conduit is substantially completely surrounded by jacket space 6, separating the walls of the conduit from the walls of the cylinder head, and also separates its walls from an adjacent conduit, and is integrally formed with the walls 40 of the cylinder head, connecting therewith at such points or portions wherein the conduit leads to openings, for establishing communication beyond the walls of the cylinder 45 head.

7 7 represents a second conduit extended longitudinally adjacent to the conduit 2, and of like formation, communicating with ports 8, 8^a and 8^b, at the base of the conduit, which open into respective engine cylinder beneath. This conduit may be termed "exhaust conduit" for the escape of the exploded gases. It is provided with a port 9 at one end of the cylinder head to communicate with an exhaust head attached to such end of the cylinder head. This end is practically square, so that the carbureter or vaporizer can be adjacently disposed to the exhaust head or exhaust conduit terminal, 55 and the radiated heat therefrom utilized to heat the air admitted into the vaporizer or carbureter to increase its efficiency. It is obvious, however, that the terminal or inlet of a respective conduit may be variously disposed around the cylinder head, although 60 65

the specific position herein has advantages, which will be hereinafter more fully set forth.

The upper walls 10, 11 and 12 of the cylinder head and conduits 2 and 7, (see Fig. 70 2), are provided with the vertical projected sleeves 13 cast integral with said walls, each providing a bearing for a valve stem. These are formed concentrically over the respective valve ports 4, 4^a and 4^b and 8, 8^a and 8^b 75 respectively, of the series. One end of each sleeve terminates externally of the upper wall 10 of the cylinder head 1.

14 represents a sleeve formed integral with the cylinder head, providing a bore 80 through the same into and through which the spark mechanism is secured and projected. This, however, can be dispensed with and the sparking mechanism for each cylinder entered into the cylinder at various other points or positions. The base 15 of the cylinder head is apertured coincidentally with apertures 16 formed in the cylinder to offer communication between the jacket space of the cylinder head and the 90 jacket space 17 surrounding the cylinder.

18 represents an inlet bore leading into the jacket space for admitting the cooling medium into the cylinder head, circulating through the same and into the jacket space 95 of each cylinder. This is an advantage in starting the engine after its water jacket has been drained, for the cold water is delivered directly against the lower portion of the cylinder head, which is the hottest portion 100 of the engine, protecting the parts and preventing them from becoming highly heated, and enters into the cylinder jacket from the upper portion thereof, protecting the cylinder head initially and before the 105 jacket space is filled, which is the first to become heated, thereby preventing the same from cracking, as is often the case where the water enters at the base of the cylinder. In such latter instance, some time is elapsed 110 before the cold water rises within the cylinder jacket space and reaches the cylinder head, which, during such interval has become highly heated and when the cold water strikes it, causes a sudden change in 115 temperature, which strains the casting, causing it to crack.

In continuous operation, the coolest water is directed against the hottest part, permitting higher compression, and as the water 120 surrounding the cylinders is warm and the engine of uniform temperature throughout, expansion of the exploded gas is aided instead of condensing it as where the cooling water enters the base of the cylinder.

19 represents sleeves cast integral with the head providing a bore completely through the head, through which the bolts pass for securing the head to the cylinders. The number for each cylinder is optional, while 130

in Fig. 1 of the drawings eight such sleeves are provided in the head for each engine cylinder.

At the terminal of the exhaust conduit, 5 an exhaust head is provided, see Figs. 7 and 8. This comprises a cylinder 20, clamped to the terminal of the exhaust conduit and in communication therewith, through a port 21. The upper portion is 10 provided with a jacket space or chamber 22 communicating with the jacket space 6 of the cylinder head and preferably above the exhaust conduit.

23 represents an overflow pipe secured 15 within the exhaust head, projecting downwardly into the exhaust chamber 24 of the exhaust head and upwardly into the jacket space or chamber 22 and extended to a higher elevation than the highest water 20 plane within the jacket space 6 of the cylinder head, the pipe functions as a discharge or overflow pipe, but which insures against draining the cylinder head below a conduit plane, keeping the same constantly immersed 25 and surrounded by water, which is advantageous in marine engines when the engine is disposed at an angular plane, due to a rocking of the boat. The overflow pipe 23 discharges into the exhaust outlet of the 30 engine, condensing and silencing the exhaust in the marine engine, wherein the discharge of both is usually directed into the water, but in stationary types of engine, the overflow pipe is directed to a water storage 35 tank, while the exhaust gases are discharged to the atmosphere. In this latter case, the tube 23 is omitted and the water is taken out from the top of chamber 22.

25 represents an air passage extended 40 around the exhaust head and formed by casing walls 26, formed integral with the exhaust head and provided with a series of orifices 27 on one side, while the opposite side is bored to receive a pipe 28, which is in 45 connection with a carburetor or vaporizer, and forms the air supply passage therefor. This construction heats the air before admitting the same to the carburetor or vaporizer adding efficiency to the gaseous vapors 50 of an explosive charge.

In Figs. 5 and 6, illustrating a modified form of cylinder head, substantially the same principles and advantages are contained, as heretofore disclosed, differing 55 only in the relative disposition of the valve ports, which are extended in a plane longitudinal of the cylinder head, instead of transverse thereto, and, therefore, the same reference characters have been applied to 60 the parts as designated for similar parts in the construction, illustrated in Figs. 1 and 2.

Having described my invention, I claim:

1. In an explosive engine, a cylinder head 65 for a multiple cylinder engine, a manifold

fuel conduit formed integral within said head, a manifold exhaust conduit formed integral within said head, each conduit surrounded by a jacket space separating the walls of the conduit from the walls of the cylinder head, and each conduit having a terminal at one end of the cylinder head. 70

2. In an explosive engine, a cylinder head for a multiple cylinder engine, a manifold fuel conduit formed integral within said head, a manifold exhaust conduit formed integral within said head, each conduit surrounded by a jacket space separating the walls of the conduit from the walls of the cylinder head, each conduit having a terminal at one end of the cylinder head, an exhaust head of double-wall formation, providing an intermediate exhaust chamber in communication with the exhaust conduit of the cylinder head, said chamber being surrounded by an air conduit open at one point to the atmosphere, a second chamber formed within said exhaust head in communication with the jacket space of the cylinder head, and an overflow pipe extended from said exhaust chamber into said second chamber. 80

3. An engine cylinder head of the nature disclosed comprising a hollow casing adapted to be removably secured to an engine cylinder, integrally and unitarily combining 95 therewith a fuel conduit and an exhaust conduit within the hollow casing in spaced parallelism, each surrounded by a jacket space with the ends of the conduits connecting with a wall of the casing providing passages 100 through the head.

4. An engine cylinder head of the nature disclosed comprising a hollow casing approximately rectangular in form unitarily combining therewith independent fuel and 105 exhaust conduits in adjacent spaced parallelism within the hollow casing.

5. An engine cylinder head of the nature disclosed comprising a hollow casing, unitarily combining therewith independent fuel and exhaust conduits in adjacent spaced parallelism within the hollow casing, each conduit separated beyond its ends from the walls of the casing to provide a surrounding 110 jacket space.

6. An engine cylinder head of the nature disclosed comprising a hollow casing integrally combining therewith a fuel conduit and an exhaust conduit adjacently parallel within the casing having their walls separated from each other and from the walls of the casing, providing passages through the head. 115

7. An engine cylinder head of the nature disclosed comprising a hollow casing unitarily combining therewith a fuel conduit and an exhaust conduit within the casing having the walls separated from each other and from the walls of the casing, to provide 120 a surrounding jacket space, each conduit 125

130

having one of its ends integrally united with the same end of the casing, and its opposing ends integrally united with the base wall of the casing to provide passages 5 through the casing.

8. An engine cylinder head of the nature disclosed comprising a hollow casing, unitarily combining independent fuel and exhaust conduits within the casing and separated from each other and the walls of the casing, said casing having a plane base wall apertured for communication between the interior of the casing and the jacket space of an engine cylinder to which the casing is 10 secured.

9. An engine cylinder head of the nature disclosed comprising a hollow casing integrally combining therewith a manifold fuel conduit and a manifold exhaust conduit longitudinally adjacently parallel within the casing, with the wall of the conduits surrounded by a jacket space, each conduit providing a common passage through the casing communicating with all of the 25 cylinders connected with the casing.

10. An engine cylinder head of the nature disclosed comprising a hollow casing integrally combining therewith a manifold fuel conduit and a manifold exhaust conduit 30 longitudinally adjacent in spaced parallelism within the casing, with the walls of the conduits surrounded by a jacket space, each conduit providing a common passage through the casing communicating with all 35 of the cylinders connected with the casing, and the base wall of said casing apertured for communication between the interior of the casing and the jacket spaces of the engine cylinders to which the casing is secured.

40 11. An engine cylinder head of the nature disclosed comprising a hollow casing unitarily combining therewith manifold fuel

and manifold exhaust conduits in adjacent spaced parallelism within the casing to provide a surrounding jacket space for each 45 conduit, and with a terminal of each conduit at the same end of the casing.

12. An engine cylinder head of the nature disclosed comprising a hollow casing unitarily combining therewith a fuel conduit 50 and an exhaust conduit both within the casing to provide a conduit surrounding jacket space, and each conduit having a terminal at the same end of the casing, a member fixed to said casing divided into three chambers, one 55 an exhaust chamber in communication with the exhaust conduit, the second communicating with the interior of the casing and said exhaust chamber, and the third affected by radiating heat of the exhaust gases within 60 the first chamber, open to the atmosphere at one portion thereof, and at an opposing portion communicating with the fuel conduit within the casing.

13. An engine cylinder head of the nature 65 disclosed comprising a hollow casing unitarily combining therewith a fuel conduit and an exhaust conduit within the casing, a member divided into three chambers, one 70 an exhaust chamber communicating with the casing exhaust conduit, a second chamber surrounding said exhaust chamber open to the atmosphere at one point and at an opposing point communicating with the casing fuel conduit, and a third chamber communicating with the interior of said casing, and with said exhaust chamber at an elevation 75 above the interior of said casing.

In testimony whereof, I have hereunto set my hand.

ERDIX ROUNDS.
